UNITED STATES PATENT OFFICE.

JOHN J. CLUIN, OF LOWELL, MASSACHUSETTS.

DESIGN FOR A BADGE.

SPECIFICATION forming part of Design No. 25,555, dated June 2, 1896.

Application filed February 24, 1896. Serial No. 580,583. Term of patent 7 years.

To all whom it may concern:

Be it known that I, JOHN J. CLUIN, a citizen of the United States, residing at Lowell, in the county of Middlesex and Commonwealth 5 of Massachusetts, have invented a new and original Design for a Badge, of which the following is a specification, said design being represented in the accompanying drawing.

The leading feature of my design consists in 10 a circular plate having at the margin thereof five equal outwardly-extending points arranged at equal angular intervals from each other; a panel on said plate on which is a shield bearing a field of stars in the upper 15 portion and a field of vertical stripes below said field of stars; on each side of said shield, from the bottom to the top thereof, a spray of leaves, the stems of said sprays bounding the curved sides of the shield and the shield concealing the leaves at the inner side of each 20 stem; a stag's head and neck arranged on said field of stripes, the lower part of said neck filling the space between the lower ends of said stems, said head having antlers which 25 extend up into said field of stars, other panels on the two lower of said five points, terminating at said stems, said last-named panels be-

ing approximately lozenge-shaped, but each having its two upper sides less convergent than its two lower sides, and three other stars, 30 one on the uppermost of the said five points and one on each of the next adjacent points.

The accompanying drawing is a front elevation of the badge, *a* being the circular plate, *b* the three upper points, and *b'* the two 35 lower points of the five points named; *c*, a nearly circular panel; *D*, the shield having a field *d* of stars and a field *d'* of stripes; *E*, the stag's head having antlers *e* arranged as described above; *F*, the stems or sprays having 40 leaves *f*; *g*, the nearly lozenge-shaped panels, partly on the points *b'* and extending up to the stems *F*; *H*, the three stars, one on each of the points *b*.

I claim as my invention—

The design for a badge, substantially as 45 herein shown and described.

In witness whereof I have signed this specification, in the presence of two attesting witnesses, this 19th day of February, A. D. 1896. 50

JOHN J. CLUIN.

Witnesses:

ALBERT M. MOORE,
JOHN I. COGGESHALL.
